(57) **CLAIM**

The ornamental design for a desktop diffuser, as shown and described.

DESCRIPTION

FIG. 1 is a top front perspective view of a desktop diffuser of the present invention;

FIG. 2 is a front side elevational view thereof, with left side, right side, and back side elevational views thereof being a mirror image of the front side elevational view; and,

FIG. 3 is a top plan view thereof.

A bottom plan view has been omitted as it does not form a portion of the claimed design. The broken lines shown in the drawings are directed to environment, are for informational purposes only, and form no part of the claimed design.

1 Claim, 2 Drawing Sheets

FIG. 1.

FIG. 2.

FIG. 3.
